CLAIM

The ornamental design for an electrical connector cover, as shown and described.

DESCRIPTION

FIG. 1 is a perspective view of an electrical connector cover showing my new design, without a lid;

FIG. 2 is a front view thereof, the rear view being mirror symmetrical;

FIG. 3 is a left side view thereof;

FIG. 4 is a right side view thereof;

FIG. 5 is a top view thereof;

FIG. 6 is a bottom view thereof; and,

FIG. 7 is a perspective view thereof, showing the electrical connector cover with a lid.
